(57) **CLAIM**

The ornamental design for a television housing, as shown and described.

DESCRIPTION

FIG. 1 is a left front perspective view of a television housing showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Broken lines are used in the figures to show environmental structure or boundaries that form no part of the design to be patented.
